UNITED STATES PATENT OFFICE.

HUGO HENKEL AND WALTER WEBER, OF DUSSELDORF, GERMANY, ASSIGNEES TO THE FIRM OF HENKEL & CIE., OF DUSSELDORF, GERMANY.

ELECTROLYTIC APPARATUS.

1,074,549.

Specification of Letters Patent. Patented Sept. 30, 1913.

Application filed June 16, 1913. Serial No. 774,053.

To all whom it may concern:

Be it known that we, HUGO HENKEL and WALTER WEBER, citizens of the German Empire, and residing at Dusseldorf, Germany, 5 have invented certain new and useful Improvements in Electrolytic Apparatus, of which the following is a specification.

Our invention relates to apparatus for the continuous production of hydrogen peroxid. 10 In a known process of synthetically making hydrogen peroxid on a commercial scale from its elements the apparatus is subjected to severe strains owing to the electrolytic process having to be carried out at a high 15 pressure, and it has been found that it is difficult to so enlarge any apparatus known heretofore that it is possible to work with it on a very large scale. Owing to the requisite pressures, such apparatus need such thicknesses of wall and such dimensions that they 20 become unmanageable and impracticable. Moreover, owing to the large dimensions the usual method of stirring can no longer be used. Continuous working of such apparatus gives rise to difficulties inasmuch as the 25 concentration of the anode liquid is so changed in a short time that irregularities occur in the progress of the reaction. Since it is highly desirable to maintain a low 30 temperature in the cathode chamber, provision must be made for this, but it is extremely difficult to cool down the cathode liquid.

A primary object of our invention is to provide an improved apparatus for continuously producing hydrogen peroxid, to which the above-mentioned drawbacks are not attached. To this end, we make the apparatus in the form of a tube. Such form of apparatus has various advantages:—Firstly, 40 it can be readily manufactured for high pressures; secondly, it can be readily maintained at predetermined temperatures, and, thirdly, owing to its small diameter the cover of the apparatus can be very readily manipulated and packed tight.

Another important advantage of our apparatus is that the anode and cathode chambers can be directly connected by means of orifices in the bottom of the diaphragm. 45 Continuous operation is thereby obtained in a very effective manner. Further, the finely distributed oxygen which forms at the anode is utilized for forming the peroxid. Furthermore, owing to causing the electrolyte 50 to flow through the anode chamber and then

through the cathode chamber, we avoid that variation of the relative concentration of the cathode and anode liquids which causes disturbances when electrolyzing with separated anode and cathode chambers. Finally, a 60 special advantage of the form we have selected for the apparatus is that it enables the diaphragm and electrodes to be so arranged that mechanical stirring in the cathode chamber is replaced by the effect of 65 the high speed of the flowing liquid.

One illustrative embodiment of our invention is represented by way of example in the accompanying drawing showing one preferred form of our apparatus in vertical section. 70

Referring to the drawing, in a long steel tube *a* of 100-150 mm. inside diameter and closed below is located a cylinder *A* of a ceramic mass cemented at its upper end to 75 the wall of the steel tube. All the remaining parts of the flanged tube as well as its cover *b* are provided with a coating of a material *e. g.* of gold or rubber, which is not attacked by sulfuric acid or other electrolytes employed. The receptacle *A* contains, firstly, the anode *E* formed as a carbon or magnetite cylinder for example. In this anode is the clay diaphragm *B* having at its lower end several apertures *B'* through which the electrolyte has direct access to the chamber in the diaphragm. In this chamber is the porous porcelain tube *C* which with the exception of a small intermediate space completely 80 fills the chamber. This tube either carries the cathode as a wire *K* wound around it, or is impregnated with the cathode metal. During electrolysis oxygen is forced by pressure through this tube *C*. For this purpose, the latter is screwed to the tube *F* which passes 85 through the cover and is connected to the oxygen compressor. The electrolyte, which has already been saturated with oxygen at the working pressure, flows through the tube *G* connected to the tube *a*, then through 90 the anode chamber of the electrolytic apparatus, thence through the bottom apertures in the diaphragm *B*, and then with considerable velocity through the narrow chamber 95 around the cathode, finally leaving the electrolytic apparatus through the tube *H*. Changes in concentration such as are unavoidable when electrolyzing with separate anode and cathode chambers are now prevented 100 owing to the electrolyte flowing continuously 105

110

through both chambers. The electrolyte is saturated with oxygen when it arrives at the cathode. The high speed attained at the cathode serves as a substitute for mechanical stirring. The oxygen issuing from the pores of the tube C assists this effect, and in addition prevents the electrolyte becoming poorer in dissolved oxygen at certain places. When passing through the narrow cathode chamber the electrolyte becomes enriched with hydrogen peroxid and enters with the desired concentration of hydrogen peroxid into the enlarged portion B² of the diaphragm B, whence it is continually discharged through the tube H.

We claim:—

1. In electrolytic apparatus of the character described, the combination of a long tubular vessel adapted to stand a high internal pressure, a ceramic cylinder in said vessel, a tubular anode in said cylinder, a tubular diaphragm having apertures at the bottom end thereof in said anode, a porous porcelain tube in said diaphragm, and a cathode connected to said porcelain tube.
2. In electrolytic apparatus of the character described, the combination of a long tubular vessel adapted to stand a high internal pressure, a ceramic cylinder in said vessel, a tubular anode in said cylinder, a tubular diaphragm having apertures at the bottom end thereof in said anode, a porous porcelain tube in said diaphragm, and a cathode connected to said porcelain tube.

lained tube in said diaphragm, and a cathode connected to said porcelain tube, said porcelain tube almost completely filling said diaphragm.

3. In electrolytic apparatus of the character described, the combination of a vertical steel tube closed at its lower end and having an inlet near the top thereof, a ceramic liner in the tube extending from the inlet to the bottom of the tube, a tubular anode in said liner, and resting on the bottom thereof, a tubular diaphragm having an enlarged portion in the steel tube above the anode and a smaller portion extending in the anode to the bottom of the steel tube, said diaphragm having apertures in the bottom end thereof at the bottom of the steel tube, a cover closing the top end of the steel tube and of the diaphragm, a porous porcelain tube attached inside to, and opening through said cover and projecting into the smaller portion of the diaphragm, a cathode wire wound around said porcelain tube, and a discharge tube passing through said cover into the enlarged portion of the diaphragm.

In testimony whereof, we affix our signatures in the presence of two witnesses.
